COMBINED SHOE LASTING AND SOLE
APPLYING APPARATUSJacob Funck and Alfred W. Dunn, Rochester,
N. Y.; said Funck assigner to said Dunn

Application August 24, 1931, Serial No. 558,900

13 Claims. (Cl. 12—7)

The object of this invention is to provide a combined shoe lasting and sole placing machine for shoes made with both the pre-welt and stitch-down processes.

Another object of this invention is to provide an apparatus for use with the stitch-down process with which the upper is perfectly fitted around the last previous to the application of the sole to the upper.

Another object of this invention is to provide an apparatus for use with the pre-welt process with which the upper and welt is held in place over a last to first have a filler and then the outer sole proper attached thereto.

Other objects and attendant advantages will become more readily apparent from the detailed description of one embodiment of the invention reference being had to the accompanying drawings in which

Figure 1 is a front elevation of a press equipped with the combined lasting and sole applying apparatus.

Figure 2 is a top plan view of the carriage support and bed of the press, the figure being viewed from the line 2x—2x of Figures 1 and 3.

Figure 3 is a vertical sectional view of the carriage support and head for stretching the upper over the last, the section being taken on the line 3x—3x of Figure 5.

Figure 4 is a bottom plan view of the head for stretching the upper over the last.

Figure 5 is a cross section of the carriage support and head, the section being taken on the line 5x—5x of Figure 3.

Figure 6 is a cross section of a portion of the carriage support with a last and upper held in place therein and the sole applied thereto.

Figure 7 is a detail perspective view of a sole. In the several figures of the drawings like reference numerals indicate like parts.

The shoe lasting and sole applying apparatus forming the subject matter of our present invention is adapted for use in both the stitch down and pre-welt processes of applying soles to shoes.

A suitable press is used in connection with this apparatus with which the sole is forced in place after it has been applied to the upper. The press illustrated in connection with our apparatus comprises an upright frame 1 which is supported on a suitable base 2. The upright frame supports a head 3 from which projects the plunger 4 carrying the pressure member 5. A suitable operating mechanism is incorporated in the frame and is operated by the rotation of the pulley 6.

The operation of the press is controlled by the

treadle 7 which, when depressed, releases the pressure member and forces the sole, which has been positioned under it, in place on the upper as will hereinafter be described.

The upright frame 1 of the press has mounted thereon the horizontal table or bed plate 7A which is adapted to have the carriage support 8 slide back and forth thereon. This carriage carries on the under side a bracket 9 which projects rearwardly below the opening 10 provided in the carriage. On the bracket 9 is mounted the supporting and centering pin 11 and the supporting bridge 12. The supporting pin is threaded so that it can be adjusted vertically on the bracket 9 and locked in the adjusted position by means of the locknuts 13 and 14. The hole thru which the stud passes in the bracket 9 is elongated so that the pin can also be adjusted laterally. The supporting pin is pointed at the top and a collar surrounds the pointed end in order to engage and support it in a predetermined position within the opening 10 of the carriage.

The supporting bridge 12 is adapted to support the toe end of the last and for this reason is slightly concaved at the top for the convexed surface of the toe end to rest therein. Both the centering pin and the supporting bridge are adjustable vertically in order to support the last and the upper in the opening 10 at the proper elevation with relation to the clamping jaws 15, 16 and 17 which surround the opening and are mounted on top of the carriage. These clamping jaws are movable on top of the carriage and are located one on each side of the opening 10 and the third at the forward end thereof. The jaws are moved simultaneously toward and away from the opening in the carriage by means of two parallel racks 18 and 19 which are mounted to slide in the carriage one on each side of the opening 10 thereof. Each rack carries a pair of pins 20, 20 and 21, 21 which engage into the angular cam slots 22, 22 and 23, 23 respectively. These cam slots are provided in the bottom of the jaws 15 and 16 respectively so that as the racks are moved back and forth, the jaws are moved toward or away from the opening 10 in the carriage. The end jaw 17 is similarly moved toward and away from the end of the opening 10 by means of the pin 24 which engages the angular cam slot 25 provided in the bottom of the jaw 17. Pin 24 is carried by the pinion 26 which is mounted on the pivot stud 27. This stud projects thru the end of the carriage and has the handle 27A keyed thereto with which the pinion is rotated. The racks 18 and 19 are adapted to mesh with

the pinion 26 at opposite sides thereof so that when the pinion is rotated, one rack is moved into the carriage while the other is moved out. In rotating the pinion in one direction, the jaws 15 and 16 therefore move toward each other while in rotating the pinion in the other direction, the jaws move away from each other. At the same time jaw 17 is operated by the pin 24 and moves in unison either toward or away from the other 10 two jaws at right angles to them.

The upper inside edge of the jaws 15, 16 and 17 have the overhanging undercut flanges 15A, 16A and 17A projecting from them. These flanges form continuations of each other and 15 their contour simulates that of the last and the upper which is to be gripped between them. When therefore a last with its upper is placed into the opening 10 of the carriage and suitably held supported therein by the supporting pin 11 20 and bridge 12, a movement of the handle 27A will move the jaws toward the upper and in the case of a pre-welt shoe which has been mounted on a last, will engage under the welt and draw the edge of the upper, to which the welt has been 25 fastened, over the edge of the last. This fits the upper tightly over the last by the time the jaws have firmly gripped the upper and last between them. In the case of a pre-welt shoe a filler is then placed on top of the last within the welt 30 after which the outer sole is cemented over the 35 welt and the filler. In this way the jaws hold the upper fitted tightly around the last while the sole is being applied thereto. A shoe thus made will therefore always have the uniform shape of the last over which it has been formed.

To finish the application of the sole to the welt, the carriage 8 is then moved back on the bed plate 7 until the last is centered and located under the pressure or die head 5. The press is 40 then operated and the die head moves down onto the sole and forces it in place on the welt under pressure.

The operation of the apparatus so far described is used in connection with pre-welt shoes, which 45 have a welt sewed to the upper. In the stitch-down process the upper is shaped over a last and the sole is applied to the edge of the upper instead of a welt.

For use on the stitch-down shoes the apparatus 50 is provided with the stretching head 30. This head has a horizontal arm 31 with which it is supported on the vertical sliding rod 32. The rod 32 is mounted in a vertical bearing 33 provided on one side of the bed plate 7 of the press 55 in which it can move up and down for a purpose that will presently appear. The stretching head 30 is provided at the top with a hollow upright 34 which is slotted at the upper end and in the slot is mounted the cam 35. Within the hollow 60 upright is mounted the plunger 36 which passes thru the stretching head and has the pressure plate 37 fastened to the lower end of it. A coil spring 38 surrounds the plunger 36 within the hollow upright 34 and normally forces the upper 65 end of the plunger against the cam surface of the cam 35. Mounted alongside of the upright 34 and its plunger 36 is a second smaller plunger 39. This latter plunger passes thru the stretching head and thru the pressure plate 37 of the plunger 36 and has the pressure plate 40 attached to the lower end of it. A coil spring 41, located 70 between the end of the sleeve 42 which surrounds the plunger 39 and the head 43 carried at the 75 top of the plunger, normally holds this plunger

with its pressure plate 40 against the under side of the pressure plate 37.

The sleeve 42 which surrounds the plunger rod 31 has keyed thereto an elongated pinion 44 which is located within the stretcher head 30. The sleeve 42 has also keyed thereto the handle 45 with which the sleeve 42 and the pinion 44 are rotated. The pinion 44 is thus mounted in the head 30 on one side of the plunger rod 36. A similar pinion 46 is mounted to rotate in the head 10 on the other side of the plunger rod 36 and this second pinion is simultaneously rotated on the rotation of the first pinion by means of the rack 47 which moves longitudinally in the head 30 and is in mesh with both of them. 15

Each of the pinions 44 and 46 has also a pair of transversely moving racks 48, 48 and 48A, 48A meshing therewith. Each pair of racks embraces a pinion between them so that on their rotation the individual racks of each pair move opposite 20 each other; that is either toward or away from each other. Suspended below the bottom of the stretcher head 30 and surrounding the pressure plates 37 and 40 are the clamping members 49, 50 and 51. These clamping members have their 25 under side shaped to correspond with the top of the jaws 15, 16 and 17 over which they are located when the stretching head is placed over the carriage as illustrated in Figure 3. Two of these 30 clamping members 49 and 50 are suspended from the rack bars 48 and 48A while clamping member 51 is suspended from the rack bar 47. When therefore the handle 45 is rotated, the pinion 44 and the other pinion 46 as well as all of the rack bars 47, 48 and 48A are operated to simultaneously 35 move the clamping members either toward or away from each other. In this way the clamping members may be operated to spread the edges of the upper as will hereinafter be described and may also be adjusted for different 40 sizes of shoes.

The clamping members 49, 50 and 51 carry a series of vertical pins 52 which are mounted to slide in suitable holes 53 provided for this purpose in clamping members. These pins are surrounded by a suitable expansion spring which normally holds their upper ends against the under side of the pressure plate 37. A downward movement of the pressure plate 37 thus forces the pointed ends of the pins 52 out of the bottom 50 of the clamping members for a purpose that will presently be described.

The stretching head is normally swung to one side of the carriage as illustrated in Figure 1. To last and apply a sole to a stitch-down shoe, 55 the last is placed and supported in the opening 10 of the carriage as above described and illustrated in dotted lines in Figure 3. The jaws of the carriage are then operated to engage the upper so that the outer edge of the upper overhangs the jaws. After this preliminary placing of the upper has been completed, the stretching head is swung over the carriage and centered over the upper and last and held in place thereon. The treadle 60 is then depressed in 60 order to pull down the sliding rod 32 against the pressure of the spring 61 which surrounds it and is located between the arm 31 and the bearing 33. In this way the head 30 is lowered onto the carriage. Because of the fact 65 that the overhanging free edge of the upper which surrounds the bottom of the last, projects angularly from the last after the upper has been drawn over the last by means of the jaws 15, 16 and 17, it is necessary to lower the stretching head 70 75

by means of the treadle 69 with its clamping members drawn inwardly. The clamping members thus engage partly or wholly within the free edge of the upper so that on their outward adjusting movement the edge of the upper is flattened and spread by the clamping members into a horizontal position over the clamping jaws 15, 16 and 17. The cam 35 mounted on the upright 34 of the head 30 is then rocked by means of the handle 35A so that the cam forces the plunger rod 38 downwardly and with it the pressure plate 37. The movement of the pressure plate in turn forces the pointed ends of the pins 52 out of the bottom of the clamping members into the folded out edge of the upper which is thus firmly anchored to the head and carriage. In turning the handle 35A to operate the cam 35 it engages the head 43 of the plunger rod 39 after it has operated the cam to force the pins into the upper. A continued movement of the handle then forces the plunger rod 39 downwardly so that the pressure plate 40 thereof is depressed and forced down onto the last located within the upper. The last is thus forced into the upper while the edges of the upper are held fixed, stretching the upper tightly over the last. After this is done the jaws of the carriage are again operated to firmly grip the last with the upper tightly stretched over it. The pressure plates of the stretching head are then allowed to move back while the head is raised and again swung to one side of the carriage to expose the last and upper which is now tightly gripped in the carriage. A sole 70 is then cemented over the last and the overhanging edge of the upper, after which the carriage is moved back under the die head 5 to have this head finish the application of the sole by forcing it in place under pressure.

40 As the gripping jaws and clamping members have the horizontal and vertical outline of the last, the edges of the upper, after being spread over them as above described, are held to conform to the outline of the bottom of the last and level therewith.

45 The bottom of the pressure member 5 is provided with a rubber pad 53 and the face of this pad is shaped to conform to the outline of the bottom of the last. The pressure member, in forcing the sole in place on the upper or welt, thus shapes the sole in conformity with the bottom of the last and the leveled edges of the upper.

50 The fact that the upper is firmly drawn over the last and fitted thereto and is held in this position before the sole or any part of it is cemented to the upper, permits the use of a blank sole on which but little extra stock need be left for trimming. A size smaller sole than has heretofore been used is therefore large enough when 55 it is applied by means of our apparatus.

55 We claim:

1. In a shoe lasting machine the combination of a carriage for supporting a last and upper, clamping means carried by said carriage for 60 clamping the edges of the upper with the last loose within the upper, pressure means above said carriage for forcing the last into the upper to stretch and fit the upper around the last, and gripping means cooperating with said pressure means for gripping the last and upper after the upper has been stretched over the last, second pressure means above said carriage and behind said first pressure means for applying a sole to the edge of the upper under pressure and guide means for guiding said carriage from below said

first pressure to below said second pressure means.

2. In a combined shoe lasting and sole applying apparatus the combination of a supporting carriage, means for locating a last with its upper in a predetermined position on said carriage, gripping members carried by said carriage and adapted to engage the upper around the bottom of the last, a stretcher head adapted to be centered over the last and upper located on said carriage, combined clamping and stretching means carried by said head and adapted to clamp and hold the free edge of the upper on said gripping members and stretch it over said gripping members away from said last, means carried by said head for forcing the last into the upper to stretch the upper around the last and means for operating said gripping members to grip the last with the upper stretched around it to permit the withdrawal of said stretcher head and allow a sole to be applied to the upper.

3. In a combined shoe lasting and sole applying apparatus the combination of a supporting carriage, means for locating a last with its upper in a predetermined position on said carriage, gripping members carried by said carriage and adapted to engage the upper around the bottom of the last, a stretcher head adapted to be centered over the last and upper located on said carriage, clamping means carried by said head and adapted to clamp and hold the free edge of the upper fixed with relation to the last, means carried by said head for forcing the last into the upper to stretch the upper around the last and means for operating said gripping members to grip the last with the upper stretched around it to permit the withdrawal of said stretcher head and allow a sole to be applied to the upper, a reciprocating die head and means for guiding said supporting carriage with the last, upper and sole under said die head to allow said die head to force the sole in place on the upper under pressure.

4. In a combined shoe lasting and sole applying apparatus, the combination of a sliding supporting carriage, supporting means carried by said carriage to support a last with its upper and welt in a predetermined position on said carriage, gripping members having substantially the outline of sections of the last grouped on said carriage with a fixed gauging point provided by said gripping members at the heel of the last so as to encircle the bottom of the last, upper and welt positioned and supported on said carriage in a predetermined position with relation to the heel thereof, means for simultaneously moving said gripping members to engage the upper under the welt and draw the upper around the last and grip the last with the upper tightly fitted around it and the welt over-hanging said gripping members to permit a filler to be placed over the last within the welt and sole applying means located in fixed relation to said gauging point of said gripping members to permit a sole to be cemented over the filler and the welt in a fixed predetermined position thereto.

5. In a combined shoe lasting and sole applying apparatus, the combination of a reciprocating supporting carriage, supporting means carried by said carriage to support a last with its upper and welt in a predetermined position on said carriage, gripping members supported on said carriage and having substantially the outline of sections of the last grouped on said carriage to encircle the bottom of the last, upper and welt

- with a fixed gauging point provided by said gripping members at the heel end thereof, means for simultaneously moving said gripping members to engage the upper under the welt and hold it 5 against said gauging point to draw the upper around the last at the sides and toe thereof and grip the last with the upper tightly fitted around it to permit a filler to be placed over the last within the welt, a reciprocating die head located 10 in fixed relation to said gauging point of said clamping members, and means for guiding said carriage in a straight horizontal movement under said die head to permit said die head to force the cemented sole in place on the filler and welt.
- 15 6. In a lasting apparatus for stitch-down shoes, the combination of supporting means for the last and upper, combined spreading and anchoring means movable down over the last within the upper and means for moving the combined 20 spreading and anchoring means laterally over the ends of the upper away from the last to temporarily hold the outer edges of the ends of the upper fixed in a horizontal position.
- 25 7. In a lasting apparatus for stitch-down shoes, the combination of supporting means for supporting the last and upper, spreading members adapted to move down onto the free edges of the upper and spread these edges into a substantially horizontal position, pins mounted to 30 slide in and out of said spreading members and means for forcing said pins into the free edges of the upper to hold the edges of the upper fixed, and means drawing the upper within its fixed edges around the last and firmly holding the upper drawn around the last.
- 35 8. In a combined lasting and sole applying apparatus the combination of supporting means for supporting a last and its upper with their bottom up, jaws having the outline horizontally 40 and vertically of the bottom of the last grouped around said supporting means, means for bringing said jaws in engagement with the upper to grip the upper and last and means movable down over the last within the upper and then outwardly over the ends of the upper away from the last to temporarily hold the outer edges of the ends of the upper fixed in a substantially horizontal position.
- 45 9. In a combined lasting and sole applying apparatus the combination of supporting means for supporting a last and its upper with their bottom up, laterally moving clamping jaws adapted to engage the upper along the outline of the bottom of the last, vertically moving spreading 50 and anchoring means movable down over the last within the upper and then outwardly away from the last over the ends of the upper to hold the outer edges of the ends of the upper and means for forcing the last into the upper 55 to stretch the upper around it while the free edges of the upper are held anchored.
10. In a combined lasting and sole applying apparatus the combination of supporting means for supporting a last and its upper with their bottoms up, laterally moving clamping jaws adapted to engage the upper along the outline of the bottom of the last, vertically moving spreading and anchoring means movable down over the last within the upper and then outwardly away from the last over the ends of the upper to hold the outer edges of the ends of the upper 10 and means for forcing the last into the upper to stretch the upper around it while the free edges of the upper are held anchored, said laterally moving clamping members being adapted to grip the upper and last after the upper has been 15 stretched around it.
11. In a shoe lasting machine the combination of last supporting means, a series of gripping members surrounding said last supporting means, said gripping members being movable horizontally and forming an expanding and contracting 20 contour of the bottom of the last with two of the opposing gripping members overlapping each other at one end to provide a fixed gauging point for the welt and upper supported on the last 25 at the heel end of the contour of the gripping members, against which gauging point the welt and upper is held while the gripping members draw the upper over the toe and sides of the last on their movement toward the last.
12. In a shoe lasting machine the combination of a series of gripping members adapted to engage the welt and upper supported on a last and draw the upper over the toe and sides of the last, said gripping members being grouped 30 to form an opening having substantially the outline of the bottom of the last and being movable horizontally so as to increase and decrease said opening between them, gauging means provided at one end of one of said gripping members 40 to hold the last against endwise movement in one direction while the gripping members draw the upper over the toe and sides of the last.
13. A shoe lasting clamp comprising a plurality of gripping members adapted to engage 45 the welt and upper supported on a last and draw the upper over the toe and sides thereof, said gripping members being grouped to form an opening between them having substantially the outline of the bottom of the last, one of said gripping members having one end thereof extending past the longitudinal center line of the opening formed by said gripping members to provide gauging means against which the welt and upper 50 at one end of the last is held while the upper is drawn over the opposite end of the last and the sides thereof.

JACOB FUNCK.
ALFRED W. DUNN.
